UNITED STATES PATENT OFFICE.

GEORGE S. HOLLISTER, OF BOSTON, AND EDMUND B. COOPER, OF NEWTON, MASSACHUSETTS, ASSIGNORS TO THE OIL WELLS RENEWAL COMPANY, OF BOSTON, MASSACHUSETTS, A CORPORATION OF MASSACHUSETTS.

OIL-WELL HEATER.

1,360,404.

Specification of Letters Patent. Patented Nov. 30, 1920.

Application filed May 7, 1919, Serial No. 295,305. Renewed June 11, 1920. Serial No. 388,350.

To all whom it may concern:

Be it known that we, GEORGE S. HOLLISTER and EDMUND B. COOPER, citizens of the United States, residing at Boston and New-
ton, in the county of Suffolk and county of Middlesex, respectively, and State of Massachusetts, have invented new and useful Improvements in Oil-Well Heaters, of which the following is a specification.

10 This invention relates to a heater adapted to be lowered like a plummet, through the usual driven tube of an oil well, and into an enlarged oil-containing cavity or chamber at the lower end of the tube, the heater
15 being provided with electrical heating means adapted to heat the oil in said chamber and melt matter partially solidified on the chamber walls, thus removing obstructions to the free entrance of oil into the chamber
20 from the surrounding oil-bearing terrain.

The invention has for its object to provide certain improvements looking to the increased efficiency, durability, and usefulness of a heater for the purpose above indicated.

The invention is embodied in the improvements which we will now proceed to describe and claim.

Of the accompanying drawings forming 30 a part of this specification,—

Figure 1 represents in section a portion of an oil well, and in elevation, a heater embodying our invention, lowered into the bottom portion of the well.

35 Fig. 2 is an enlarged section on line 2—2 of Fig. 1.

Fig. 3 is a section on line 3—3 of Fig. 2.

Fig. 4 is a side view of a portion of one 40 of the insulating cores hereinafter described.

Fig. 5 is an end view of the core shown by Fig. 4.

Fig. 6 is a view similar to Fig. 4, showing a different form of core.

Fig. 7 is an end view of the form shown 45 by Fig. 6.

Fig. 8 is a fragmentary view showing in elevation, portions of the suspending cable, and partly in section portions of the conducting cable hereinafter referred to.

50 Fig. 9 is a section on line 9—9 of Fig. 7.

Fig. 10 is a diagram illustrating the electrical connections within the casing.

Fig. 11 is a view similar to Fig. 6, show-

ing a different construction of the liquid-tight casing hereinafter referred to.

Fig. 12 is a section on line 12—12 of Fig. 11.

The same reference characters indicate the same parts in all of the figures.

Our improved heater includes a plurality 60 of spaced apart insulating cores 12 or 12^a, each having external grooves to engage resistance coils, and internal ducts to conduct coil-connecting wires. As shown by Figs. 4 and 5, each core may be cylindrical and 65 provided with a helical groove 13. As shown by Figs. 6 and 7, each core may be of approximately triangular form and provided with interrupted coil-receiving grooves 13^a. The ends of the cores are preferably 70 reduced to form studs 14 at their opposite ends, the studs at the lower ends of the grooves being engaged with sockets in a lower head 15 forming a part of the casing hereinafter described, the studs at the upper 75 ends of the grooves being engaged with sockets in a plate 16 inserted in the casing. Each core is provided with a longitudinal central duct 17 through which pass the coil-connecting wires hereinafter described.

The above-mentioned casing is of liquid-tight construction to exclude oil from its interior, and may be composed of an elongated tubular body 18 having a liquid-tight connection with the lower head 15, and an upper head 19 having a liquid-tight connection with the upper end of the body, the upper head having an opening 20 for the passage of insulating lead wires 21 and 22.

Engaged with the core grooves above described are helical resistance coils 23 connected in series by coil-connecting wires 24 extending through the ducts 17 and from coil to coil, the first coil 23 of the series and the last conducting wire 24 of the series being connected respectively with the lead wires 21 and 22, as indicated by Fig. 10.

The portions of the lead wires 21 and 22 external to the casing, may be of indeterminate length, to extend from mouth to 100 bottom of an oil well. Said external portions are inclosed in a flexible tube or sheath 25 of oil-resisting soft metal such as lead, a liquid tight connection being provided between the sheath and the casing at the opening 20. Said connection is provided by a

stuffing-box 26 of any suitable construction, attached to the upper head 19, and receiving the lower end of the sheath 25, the stuffing-box being provided with an adjustable 5 follower or gland adapted to compress packing interposed between the inserted portion of the sheath 25 and the wall on the stuffing-box.

The sheath 25 and the inclosed portions 10 of the lead wires constitute a conducting cable.

Extending beside the conducting cable is a suspending cable 28, which may be a wire 15 rope, and may be engaged with the casing by means of a hook 30 attached to the upper head 19, as shown by Fig. 2.

We prefer to couple the conducting cable to the suspending cable by spaced apart 20 couplings 31, as indicated by Figs. 8 and 9, and formed to permit the winding of the two cables upon a drum above the mouth of the well, the couplings being stored with the cables on the drum. Each coupling is provided with clamping means whereby it is 25 firmly engaged with the cables. As best shown by Fig. 9, each coupling is preferably composed of a bent metal strip 31, formed to embrace portions of the cable 28 and sheath 25, and bolts 31^a connecting the arms 30 of said strip and having heads and nuts bearing on said arms.

The casing is formed to be lowered through the usual driven tube 33 of the oil well into the usual cavity or chamber 34 35 with which said tube communicates, as shown by Fig. 1. When the casing is thus lowered and the electric circuit is closed, the coils 23 are heated and the casing radiates heat into the body of oil in the chamber 34.

40 The lead wires 21 and 22 are inclosed in tubes or coverings 21^a and 22^a of insulating material. The liquid-tight connection provided by the stuffing-box 26, between the casing, and the sheath 25, prevents the 45 entrance of oil into the casing through the head 19. The casing has no opening excepting that in the head 19, so that oil is excluded from its interior. The sheath 25 protects the portions of the insulating coverings 21^a and 22^a which are external to the casing, from injury by oil, these coverings being usually of a material liable to disintegration by oil. The couplings 21 connecting the conducting cable with the suspending cable, prevent independent strain on the conducting cable tending to separate the sheath 25 from the stuffing-box 26.

60 The casing is preferably provided at its opposite ends with tapered portions 36, to facilitate the entrance of the casing into the well tube 33.

Figs. 11 and 12 show a different construction of the liquid-tight casing designed to present more heat-radiating surface to the oil in the chamber 34 than the form shown 65 by Figs. 1, 2 and 3. The said casing includes a chambered portion formed by a cylindrical wall 37, the head 19 and a lower head or bottom 38 having apertures for the lead wires and the conducting wires, a series 70 of independent radiating tubes 39 inclosing the cores, and brazed, or otherwise rigidly secured to the head 38 to form a liquid-tight connection therewith, and a head 40 to which the lower ends of the tubes 39 are similarly 75 connected by brazing or otherwise, to form liquid-tight joints between the lower ends of the tubes 39 and the head 40.

As will be seen by reference to Fig. 12, the tubes 39 are spaced apart so that all 80 portions of their peripheries are in contact with the oil, the diameter of the tubes 39 being such that they collectively present more radiating surface than the periphery of the tubular body 18. It will be seen that 85 the independent tubes 39 constitute a means equivalent to the tubular body 18 for inclosing and supporting the insulating cores.

We claim:

1. An oil well heater comprising spaced 90 apart insulating cores, resistance coils and coil-connecting wires engaged with said cores, a liquid-tight casing inclosing said cores, coils and wires, and including an upper head having an opening, and provided 95 with a stuffing-box coinciding with said opening, a conducting cable composed of elongated lead wires connected with said coils and extending through said opening and stuffing-box, and an oil-resisting flexible 100 sheath inclosing the exposed portions of the lead wires outside the casing and extending into the stuffing-box, said stuffing-box and the portion of the sheath within the stuffing-box, constituting a liquid-tight packing, preventing access of oil to said opening and lead wires, and a suspending cable secured to said head and extending beside the conducting cable.

2. An oil well heater substantially as 110 specified by claim 1, comprising also couplings rigidly secured to the conducting cable and to the suspending cable at spaced intervals, and formed to be stored with the cables on a drum, said couplings preventing 115 the withdrawal of the conducting cable from the stuffing-box by strain exerted on the cables.

In testimony whereof we have affixed our signatures.

GEORGE S. HOLLISTER.
EDMUND B. COOPER.
